LEAD SCAVENGER COMPOSITIONS

Venard E. Yust, Alton, and John L. Bame, East Alton, Ill., assignors to Shell Development Company, Emeryville, Calif., a corporation of Delaware

No Drawing. Application June 27, 1952
Serial No. 296,096

20 Claims. (Cl. 44—69)

This invention relates to compositions which are useful as scavengers with lead anti-knock compounds.

The use of lead compounds in gasolines to increase the octane ratings thereof is extremely widespread. There are, however, several rather serious adverse effects which accompany the use of leaded gasolines. One of these effects, the deposition of various lead compounds within the combustion chambers of the engines, has been at least partially remedied by the use of halohydrocarbon scavengers such as ethylene dibromide. Another adverse effect, which has been attributed to the lead anti-knock compounds, is mis-firing of the engine due to spark plug fouling. This spark plug fouling is quite prevalent under conditions of high temperature engine operation and, particularly in the case of aircraft engines, is a very serious type of trouble.

It is, therefore, an object of the present invention to overcome the previous shortcomings arising from the use of leaded gasolines. It is a further object to provide novel scavenger compositions for use with lead anti-knock compounds and in gasoline fuels. Another object is to provide novel fuel compositions containing said scavenger compositions. Other objects will be apparent hereinafter.

It has now been found that the use, as a lead scavenger in leaded gasoline fuel compositions, of a mixture of a halohydrocarbon scavenger and of a smaller amount of certain phosphorus compounds will result in greatly improved operation of spark ignition internal combustion engines. More particularly, the use of such scavenger compositions substantially eliminates spark plug fouling, or at least minimizes such fouling to a point where it is no longer a material consideration in engine operation. This outstanding advantage is obtained without having the anti-knock characteristics of the fuel deleteriously affected by the presence of the scavenger compositions.

The phosphorus compounds in the present scavenger compositions will be referred to hereinafter as "anti-fouling compounds."

The halohydrocarbon scavenger which makes up the major proportion of the scavenger compositions of the present invention may be, for example, any of the numerous halogen scavenger compounds already known, such as ethylene dibromide and ethylene dichloride (U. S. 2,398,281), acetylene tetrabromide (U. S. 2,490,606), hexachloropropylene; mono- and polyhalo propanes, butanes and pentanes (U. S. 2,479,900 and U. S. 2,479,902), polyhalo alkyl benzenes (U. S. 2,479,901 and U. S. 2,479,903), and the like, having a volatility between about 100 and about 0.1 mm. Hg at 50° C.

The phosphorus anti-fouling compounds of the present invention are those having the following formula:

wherein X is O, S, or NR, R is a hydrogen atom or an organic radical, at least one R being a cyclic organic radical, x is an integer from 1 to 3, inclusive, y is an

2

integer from 0 to 1, inclusive, z is an integer from 0 to 2, inclusive, and $x+z=3$.

A preferred group of the foregoing class of compounds, obtained when X is an oxygen atom, is made up of phosphonic and phosphonous acids and the mono and diesters thereof; phosphinic and phosphinous acids and their esters; and primary, secondary and tertiary phosphines and phosphine oxides. Of the above group, the neutral esters and tertiary phosphines and tertiary phosphine oxides are preferred.

It will be noted that at least one of the R's in the above formula must be a cyclic organic group. So long as this requirement is satisfied, the remaining R's may be either hydrogen atoms or aliphatic organic groups; it is preferred, however, that all of the R's be organic groups. It is further preferred that all of the organic groups be cyclic groups. Best results are obtained when the cyclic groups are attached directly to the phosphorus atom or phosphorus oxide nucleus rather than being attached through an aliphatic chain. The same is true when the sulfur or nitrogen analogues are used in place of the oxygen-containing compounds.

The cyclic groups may be heterocyclic or carbocyclic, and the latter may be either cycloaliphatic or aromatic.

25 Alkyl groups, up to about 12 or 15 carbon atoms, substituted upon the cyclic groups markedly increase the anti-fouling effectiveness of the present phosphorus compounds. While substituents other than hydrocarbon radicals do not, in general, adversely affect the efficiency 30 of the phosphorus compounds as anti-fouling agents, it is preferred that the R groups be unsubstituted hydrocarbyl radicals.

When using the scavenger compositions of the present invention, the total amount of halogen scavenger plus 35 anti-fouling agent present will generally fall between about 0.6 and about 1.5 theories, based upon the lead content of the gasoline, but may advantageously be as low as 0.4 or as high as 2.0 in some cases. The preferred range is from about 0.9 to about 1.2 theories.

40 The ratio of the two components of the scavenger composition is rather important. For example, if the proportion of halogen scavenger present is too large, excessive wear and corrosion of certain operating parts, such as exhaust valves and valve guides, is noted. If too small a quantity of halogen scavenger is used, the lead deposits are not effectively scavenged. If too small a quantity of the anti-fouling compound is used, the spark plug fouling will not be materially reduced; and if too much of that compound is present the amounts of deposits and the plug 45 fouling are both increased. In general, the theory ratio of the halogen scavenger or scavengers to the anti-fouling agents should be between about 3:2 and about 100:1. For best results this ratio should be between about 2:1 and about 15:1. As an additional limitation, the total 50 scavenger mixture and the ratio of components therein should be adjusted so that the anti-fouling compound is present in an amount of between about 0.01 and about 0.6 theories, and preferably between about 0.05 and about 0.4 theories. It is preferred that the weight concentration 55 of the anti-fouling additive in the fuel be kept below 0.1%. It is to be understood that more than one of the compounds from each class (i. e., halogen scavenger or anti-fouling agent), may be used in any single composition, just so the total quantity of each type falls within the limits set forth above.

60 The term "theory," when used in conjunction with a halogen scavenger compound, designates the amount of scavenger required to react stoichiometrically with a given amount of lead anti-detonant so that all of the lead atoms and all of the halogen atoms form $PbBr_2$ or $PbCl_2$. In other words, a theory of scavenger is an amount which

contains two atomic proportions of halogen for each atomic proportion of lead in the anti-detonant, or, a theory of the halohydrocarbon scavenger is one mol of the halohydrocarbon scavenger divided by one-half the number of halogen atoms per molecule, for each gram atom of lead in the lead anti-detonant present, and therefore, the number of theories of halohydrocarbon scavenger present in a given composition is equal to the number of mols of halohydrocarbon scavenger present multiplied by one-half the number of halogen atoms per molecule, for each gram atom of lead in the lead anti-detonant present. As applied to the anti-fouling compound, the term "theory" designates the amount required to react stoichiometrically with the lead so that all of the lead atoms and all of the phosphorus atoms form $Pb_3(PO_4)_2$. Therefore a theory of the anti-fouling compound is one mol thereof multiplied by two-thirds (that is, two-thirds of a mol of the anti-fouling compound), for each gram atom of lead in the lead anti-detonant present, and therefore the number of theories of anti-fouling compound present in a given composition is equal to the number of mols of the anti-fouling compound present multiplied by three-halves, for each gram atom of lead in the lead anti-detonant present.

While it is to be understood that the present compositions may be utilized in any leaded gasoline fuel, the compositions are of particular importance with respect to use in reciprocating internal combustion engine gasoline fuels, and especially such aviation fuels. This is true because of the relatively more frequent occurrence of spark plug fouling in aviation engines, with the greater inherent danger to human life in the case of failures of such engines. In addition to the lead anti-detonant and the scavenger composition, the gasoline fuels, or the concentrates for addition thereto may also contain corrosion inhibitors and stabilizers, such as 2,4-dimethyl-6-tertiary butyl phenol and other alkyl phenols, N,N'-dibutyl p-phenylene diamine, hydroquinone, phenyl-alpha-naphthylamine, N-butyl-p-aminophenol, alpha-naphthol, etc., dyes and the like.

By the term "leaded gasoline," and the terms of similar import, is meant a petroleum fraction boiling in the gasoline hydrocarbon range (between about 50° F. and about 450° F.) to which has been added a small amount, usually between about 1 and about 6 cc. per gallon, of a metallo-organic, usually an organo-lead, anti-knock compound, such as a tetra-alkyl lead, e. g., tetra-ethyl lead, tetra-i-propyl lead, etc.

The fuels to which the present scavenger compositions are added are preferably those which are relatively stable with respect to oxidation or gum formation. The stability may result from the use of stable base stocks such as aviation alkylate, straight run gasoline fractions, or other fractions which have been highly refined to remove olefins, or the stability may result from the use of oxidation stabilizers, such as those mentioned above. A few of the phosphorus compound anti-fouling agents of the present invention are known to have slight oxidation inhibiting properties; these properties are so weak, however, that it is much preferred that an additional oxidation inhibitor, i. e., a non-phosphorus stabilizer, be used in the present gasoline compositions.

As indicated above, the scavenger compositions of this invention are particularly useful in aviation gasoline. By the term "aviation gasoline" is meant a relatively high grade of gasoline fuel used in aviation engines, as distinguished from the lower quality gasolines, or "motor fuels" used in automotive engines. Aviation fuels have a more closely specified boiling range, generally running from a minimum of about 100° F. to a maximum of about 350° F. The octane number of such fuels is generally in excess of 100. Because of the demand for high quality, thermally cracked fractions are never used in aviation gasolines. Catalytically cracked fractions may sometimes be used, but only after treatment to remove

olefins. One of the reasons for the restrictions upon incorporation of cracked gasolines in aviation fuels is that the oxidation stability of aviation fuels must be much greater than that required for motor fuels. For example, when tested according to a method such as described in the patent issued to Thomas W. Bartram, U. S. 2,256,187, an aviation fuel base stock will go well beyond 4 or 5 hours before the oxygen pressure will have decreased by 5 pounds per square inch.

The following are examples of compositions suitable for use according to the present invention:

Example I:

Tetra-ethyl lead
1.0 theory ethylene dibromide
0.2 theories bis-(3,5-dimethylphenyl) 2,5-dimethylbenzene phosphonate

Example II:

Tetra-ethyl lead
1.0 theory ethylene dibromide
0.1 theory phenyl dibenzene phosphonite

Example III:

Tetra-ethyl lead
1.0 theory ethylene dibromide
0.1 theory tri-(2,4-dimethylphenyl) phosphine

Example IV:

Tetra-ethyl lead
1.0 theory acetylene tetrabromide
0.4 theory S,S-diethyl benzene dithiophosphonite

Example V:

80 octane aviation gasoline containing, per gallon
0.5 cc. tetra-ethyl lead
1.0 theory ethylene dibromide
0.2 theory diphenyl benzene phosphonate
0.02 gr. 2,4-dimethyl-6-tert.-butylphenol

Example VI:

Aviation alkylate containing, per gallon
4.6 cc. tetra-ethyl lead
1.0 theory ethylene dibromide
0.04 gr. 2,4-dimethyl-6-tert.-butylphenol
0.1 theory tri-(p-xenyl) phosphine oxide

Example VII:

Tetra-ethyl lead
1.2 theories hexachloropropylene
0.2 theory diallyl benzene phosphonate

Example VIII:

Tetra-ethyl lead
0.8 theory ethylene dibromide
0.2 theory dimethyl p-dimethylaminophenyl phosphine sulfide

Example IX:

Tetra-ethyl lead
1.5 theories hexachlorobutadiene-1,3
0.1 theory di-(3,5-dimethylcyclohexyl) cyclohexane-phosphonite

Example X:

76 octane motor fuel containing, per gallon
2.1 cc. tetra-ethyl lead
1.0 theory ethylene bromide
0.5 theory ethylene dichloride
0.2 theory diphenyl benzenethionophosphonate
0.06 gr. N,N'-dibutyl p-phenylene diamine

Example XI:

115/130 grade aviation gasoline containing, per gallon
4.6 cc. tetra-ethyl lead
1.0 theory ethylene dibromide
0.2 theory cyclopentadienyl dibenzene phosphonate
0.04 gr. 2,4-dimethyl-6-tert.-butylphenol

Example XII:

Tetra-ethyl lead
0.5 theory ethylene dibromide
0.1 theory tri-(2,5-dimethylphenyl) phosphine oxide

Example XIII:

Tetra-ethyl lead
0.8 theory ethylene dichloride
0.2 theory diphenyl benzenephosphonite

Example XIV:

Tetra-ethyl lead
1.0 theory ethylene dibromide
0.1 theory phenyl dibenzene phosphinate

Example XV:

Motor gasoline containing, per gallon
1.6 cc. tetra-ethyl lead
1.0 theory hexachloroethane
0.2 theory triphenyl phosphine
0.06 gr. N-butyl-p-aminophenol

Example XVI:

Tetra-ethyl lead
1.0 theory ethylene dibromide
0.05 theory tri-(2,5-dimethylphenyl) phosphine

Example XVII:

Tetra-ethyl lead
1.0 theory ethylene dibromide
0.5 theory di-(2-methyl-3-indolyl) phosphinic acid

Example XVIII:

Tetra-ethyl lead
0.8 theory ethylene dibromide
0.2 theory ethyl benzene(p-methylbenzene) phosphinate

Example XIX:

Tetra-ethyl lead
1.0 theory ethylene dichloride
0.1 theory tri- α -naphthyl phosphine

Example XX:

Tetra-ethyl lead
1.0 ethylene dibromide
0.5 theory ethylene dichloride
0.5 theory diocetyl styrenephosphonate

Example XXI:

Tetra-ethyl lead
1.0 theory ethylene dibromide
0.1 theory N-phenyl di-(2,5-dimethylbenzene)-phosphinic amide

Example XXII:

Tetra-ethyl lead
1.0 theory ethylene dibromide
0.1 theory tri-(2,4-dimethylphenyl) phosphine oxide

Example XXIII:

Tetra-ethyl lead
1.0 theory ethylene dibromide
0.1 theory tri-(3,3,5-trimethylcyclohexyl) phosphine

It is to be understood that the order of mixing the various constituents of the present compositions is immaterial. For example, the anti-fouling compound may be added to a gasoline which already contains the anti-knock compound and halogen scavenger. Likewise, the metallo-organic anti-knock agent, the halogen scavenger and the anti-fouling compound may be first mixed, stored and handled as a concentrate, and added to the gasoline at a later time. A typical concentrate of this latter type has approximately the following composition:

	Weight percent
Tetra-ethyl lead	55-60
Ethylene dibromide	25-30
Tricresyl phosphine	10-15
Kerosene, inhibitor, dye stabilizer, etc.	3-6

Under other circumstances it may be desirable to mix the halogen scavenger and the anti-fouling agent, or the anti-knock agent and the anti-fouling agent, in the desired relative proportions and handle or store this mixture, with or without stabilizers, inhibitors, etc., as a concentrate for later incorporation with the other components of the ultimate fuel composition.

The present application is a continuation-in-part of our copending application Serial No. 242,309, filed Au-

gust 17, 1951, now abandoned, which is in turn a continuation of our application Serial No. 167,376, filed June 10, 1950, now abandoned.

We claim as our invention:

- 5 1. A fuel composition for internal combustion engines consisting essentially of a stable gasoline, a minor effective anti-detonant amount of a tetra lower alkyl lead anti-detonant, and a scavenger mixture for said anti-detonant consisting essentially of a halohydrocarbon scavenger and of a phosphorus compound having the formula:

wherein X is a chalcogen atom having an atomic number of from 8 to 16, inclusive; R is selected from the 15 group consisting of hydrogen atoms and hydrocarbyl radicals, at least one R being a carbo-cyclic radical; x is an integer from 1 to 3, inclusive; y is an integer from 0 to 1, inclusive; z is an integer from 0 to 2, inclusive; and x+z=3; said halohydrocarbon scavenger and said phosphorus compound being present in amounts such that where (a) is the number of mols of said halohydrocarbon scavenger present multiplied by one-half the number of halogen atoms per molecule, for each gram atom of lead in the lead anti-detonant present, and (b) is the number of mols of said phosphorus compound present multiplied by three-halves, for each gram atom of lead anti-detonant present, the total of (a) plus (b) is from about 0.4 to about 2.0, (b) is from about 0.01 to about 0.6, and the ratio of (a) to (b) is from about 3:2 to about 100:1.

- 20 2. A gasoline additive composition consisting essentially of a tetra lower alkyl lead anti-detonant and a scavenger mixture for said anti-detonant consisting essentially of a halohydrocarbon scavenger and of a phosphorus compound having the formula:

wherein X is a chalcogen atom having an atomic number of from 8 to 16 inclusive; R is selected from the group 40 consisting of hydrogen atoms and hydrocarbyl radicals, at least one R being a carbo-cyclic radical; x is an integer from 1 to 3, inclusive; y is an integer from 0 to 1, inclusive; z is an integer from 0 to 2, inclusive; and x+z=3; said halohydrocarbon scavenger and said phosphorus compound being present in amounts such that where (a) is the number of mols of said halohydrocarbon scavenger present multiplied by one-half the number of halogen atoms per molecule, for each gram atom of lead in the lead anti-detonant present, and (b) is the number of mols of said phosphorus compound present multiplied by three-halves, for each gram atom of lead anti-detonant present, the total of (a) plus (b) is from about 0.4 to about 2.0, (b) is from about 0.01 to about 0.6, and the ratio of (a) to (b) is from about 3:2 to about 100:1.

- 45 3. A lead scavenging composition for use with a leaded anti-detonant gasoline fuel for internal combustion engines consisting essentially of a halohydrocarbon scavenger and of a phosphorus compound having the formula:

wherein X is a chalcogen atom having an atomic number of from 8 to 16, inclusive; R is selected from the group 55 consisting of hydrogen atoms and hydrocarbyl radicals, at least one R being a carbo-cyclic radical; x is an integer from 1 to 3, inclusive; y is an integer from 0 to 1, inclusive; z is an integer from 0 to 2, inclusive; and x+z=3; said halohydrocarbon scavenger and said phosphorus compound being present in amounts such that where (a) is the number of mols of said halohydrocarbon scavenger present multiplied by one-half the number of halogen atoms per molecule, and (b) is the number of mols of said phosphorus compound present multiplied by three-halves, the ratio of (a) to (b) is from about 3:2 to about 100:1.

4. A composition in accordance with claim 1 wherein each R is a carbocyclic radical.
5. A composition in accordance with claim 1 wherein at least one R is an aryl radical.
6. A composition in accordance with claim 1 wherein each R is an aryl radical.
7. A composition in accordance with claim 1 wherein at least one R is an alicyclic radical.
8. A composition in accordance with claim 1 wherein each R is an alicyclic radical.
9. A composition in accordance with claim 1 wherein the phosphorus compound has the formula:

wherein X is a chalcogen atom having an atomic number of from 8 to 16, inclusive; R is a carbocyclic radical; and y is an integer from 0 to 1, inclusive.

10. A composition in accordance with claim 1 wherein the stable gasoline is a stabilized gasoline, the tetra lower alkyl lead anti-detonant is tetraethyl lead, the halohydrocarbon scavenger is a mixture of ethylene dibromide and ethylene dichloride, the phosphorus compound is bis(3,5-dimethylphenyl) 2,5-dimethylbenzene-phosphonate, and (b) is from about 0.05 to about 0.4.

11. A composition in accordance with claim 1 wherein the tetra lower alkyl lead anti-detonant is tetraethyl lead, the halohydrocarbon scavenger is ethylene dibromide, the phosphorus compound is trixylene-phosphine oxide, and (b) is from about 0.05 to about 0.4.

12. A composition in accordance with claim 1 wherein the tetra lower alkyl lead anti-detonant is tetraethyl lead, the halohydrocarbon scavenger is ethylene dibromide, the phosphorus compound is tri-(2,5-dimethylphenyl)phosphine, and (b) is from about 0.05 to about 0.4.

13. A composition in accordance with claim 1 wherein the stable gasoline is a stabilized aviation gasoline boiling within the range 100° F. and 350° F., containing no thermally cracked gasoline fractions and no ole-

finic catalytically cracked gasoline fractions, the tetra lower alkyl lead anti-detonant is tetraethyl lead, the halohydrocarbon scavenger is ethylene dibromide, the phosphorus compound is tri-(3,3,5-trimethylcyclohexyl)phosphine, and (b) is from about 0.05 to about 0.4.

14. A composition in accordance with claim 1, wherein each R is a hydrocarbyl radical, (b) is from about 0.05 to about 0.4, and the weight concentration of the phosphorus compound in the fuel is below 0.1%.

15. A composition in accordance with claim 6, wherein X is oxygen, (b) is at least about 0.05, and the ratio of (a) to (b) is up to about 15:1.

16. A composition in accordance with claim 14, wherein the bonding valence of each carbocyclic R is on a ring carbon atom.

17. A composition in accordance with claim 16, wherein the halohydrocarbon scavenger comprises ethylene dibromide, and X is oxygen.

18. A composition in accordance with claim 16, wherein the phosphorus compound has the formula:

wherein y is an integer from 0 to 1, inclusive.

19. A composition in accordance with claim 18, wherein X is oxygen, (b) is from about 0.05 to about 0.4, and the weight concentration of the phosphorus compound in the fuel is below 0.1%.

20. A composition in accordance with claim 19, wherein the bonding valence of each carbocyclic R is on a ring carbon atom, and the halohydrocarbon scavenger comprises ethylene dibromide.
